Attorney

UNITED STATES PATENT OFFICE.

CHARLES FLINT, OF SPOKANE, WASHINGTON.

HAND-LEVEL.

1,219,095.

Specification of Letters Patent. Patented Mar. 13, 1917.

Application filed April 26, 1916. Serial No. 93,669.

To all whom it may concern:

Be it known that I, CHARLES FLINT, citizen of the United States, residing at Spokane, in the county of Spokane and State of Washington, have invented certain new and useful Improvements in Hand-Levels, of which the following is a specification.

This invention relates to new and useful improvements in levels and more particularly to a hand level and the primary object is to provide a level of this character which is provided with an auxiliary or secondary level designed for use in connection with the estimation of yardage for excavation work and the like.

A further object of the invention resides in providing an improved level which is provided with expandable ends so that the same may be made in pocket size and capable of extension for accurate work.

Another object of the invention resides in providing an improved indicator therefor capable of being read from various positions and provided with means for locking the same against movement when the device is not in use.

A still further object resides in providing a device which is simple and durable in construction, inexpensive to manufacture and one which will be very efficient and useful in operation.

With these and other objects in view my invention consists in the novel features of construction, combination and arrangement of parts, as will be hereinafter referred to and more particularly pointed out in the specification.

In the accompanying drawings forming a part of this application:—

40 Fig. 1 is a side elevation partly in section showing clearly the indicator applied to use;

Fig. 2 is a side elevation of the device applied on an inclined plane and showing the auxiliary or secondary level in operation;

Fig. 3 is a vertical transverse section through the device, as seen on the line 3—3 of Fig. 1;

Fig. 4 is a top plan view thereof;

50 Fig. 5 is a side elevation disclosing the expandable ends in extended position;

Fig. 6 is a perspective view of one of the ends removed;

Fig. 7 is a perspective view of the indicator casing removed;

Fig. 8 is a detailed section showing the locking means for the indicator;

Fig. 9 is an end elevation of the device;

Fig. 10 is a vertical transverse section as seen on the line 10—10 of Fig. 5; and

Fig. 11 is a similar view as seen on the line 11—11 of Fig. 5.

In describing the invention, I shall refer to the drawings in which similar reference characters designate corresponding parts throughout the several views and in which 60 1 designates a body having longitudinal slots 2 and 3 therein projecting from opposite ends in which fit the web-like portions of the sliding and expandable end sections 4 and 5 respectively. The slots 2 and 3 are somewhat irregular in design as clearly shown in Figs. 10 and 11 of the drawings and the web-portions of said expandable end sections are designed in cross section to conform thereto, and each end section is further provided with a dove-tail rib 6 which fits in the dove-tail slot 7 in the member 1.

Mounted in an opening 8 in the central portion of the body 1 is a casing 9 which contains the indicator as will be described presently. Mounted in this casing are two opposed faces or dials 10 which have scales arranged in arcs of 200 degrees or over and properly graduated. The edges of these 70 disks or faces 10 are beveled inwardly and also graduated as shown at 11 whereby the indicator may be read from various angles above the level proper. A pendulum-like indicator 12 is provided, the same being fulcrumed intermediate of its ends between the disks or faces 10, as shown at 13, and the upper or outer portion of the same has a key head 14 formed or secured thereto, the ends of which are bent downwardly, 80 whereby said indicator may be read from all angles and positions.

I have also provided a locking means for the indicator to prevent undue wear and tear on the latter when not in use. To this 80 end a thumb screw 15 is provided which operates in a threaded opening in the front wall of a casing 9 at the lower portion of the latter, the extreme inner end of said screw being provided with a cone-shaped 100 head piece 16. A fulcrumed locking member or latch 17 is provided within the casing 9 just below the lower portion of the indicator 12, as shown in Fig. 8 of the drawings, same being normally held out of en- 110

gagement with the member 12 by means of a coil spring 18. It is obvious that the cone head 16 of the screw 15 is adapted for engagement with one end of the member 17 whereby to move said latter member on its fulcrum point against the tension of the spring 18 and cause said member to contact with the member 12, thus locking the latter against movement.

On one end of the body 1 is provided an auxiliary or secondary level which consists of an arm 19 pivoted as at 20 and adapted to be received in a groove 21 in one side face of said body. The inner pivoted end 22 of said auxiliary level is provided with a head or the like which has degree divisions thereon coöperating with a mark on the body 1. The coöperation of the main level and the secondary level will effect a great saving in time and labor for certain classes of work such as in the estimation of yardage for excavation work. The level proper may be set with the grade or slope upon which a cut is to be made while the secondary level may be set level and used as a sight to secure a point that will give the leg of the triangle upon which excavation estimates are being made. It is also necessary at times to obtain a particular angle both above and below the base position and in such an instance, a reading may be taken on the indicator and by reading the angle of a secondary level, the proper

angle may be obtained either with respect to the horizontal, or to the whole angle.

It will be seen from the foregoing that I have provided a very efficient device for carrying out the objects of this invention and one which is very simple and inexpensive to manufacture.

While I have particularly described the elements best adapted to perform the functions set forth, it is obvious that various changes in the form, proportion and in the minor details of construction may be resorted to, without departing from the spirit or sacrificing any of the principles of the invention.

Having thus described my invention, what I claim and desire to secure by Letters Patent, is:—

In a level of the class described, a stock, a pendulum-like indicator pivoted intermediate of its ends within said stock, a locking mechanism for said indicator comprising a spring controlled fulcrumed latch member normally held out of engagement therewith, and means for manually disposing said locking mechanism in its engaging position, said means consisting of a thumb-screw provided with a cone-shaped head-piece adapted to engage said latch-member.

In testimony whereof I affix my signature.

CHARLES FLINT.
